UNITED STATES PATENT OFFICE

SAMUEL A. MARSHAK, OF BROOKLYN, NEW YORK

DESIGN FOR BOTTLE SUPPORT OR SIMILAR ARTICLE

Application filed March 13, 1931. Serial No. 39,071. Term of patent 7 years.

To all whom it may concern:

Be it known that SAMUEL A. MARSHAK, citizen of the United States, and resident of Brooklyn, in the county of Kings and State of New York, has invented a new, original, and ornamental Design for a Bottle Support or Similar Article, of which the following is a specification, reference being had to the accompanying drawings forming part thereof, in which,

Fig. 1 is a perspective view of a bottle support embodying my new design; and
Fig. 2 is a top plan view thereof.

I claim:

The ornamental design for a bottle support or similar article, substantially as shown.

Dated, March 11, 1931.

SAMUEL A. MARSHAK.
